Primary Examiner — Marianne Pandozzi*Assistant Examiner* — Jae Liang*(74) Attorney, Agent, or Firm* — Cantor Colburn LLP(57) **CLAIM**

The ornamental design for a coffee carafe, as shown and described.

DESCRIPTION

FIG. 1 is a first perspective view of a coffee carafe showing a first embodiment of my new design;

FIG. 2 is second perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side view thereof;

FIG. 8 is a right side view thereof;

FIG. 9 is a first perspective view of a coffee carafe showing a second embodiment of my new design;

FIG. 10 is a second perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a left side view thereof; and,

FIG. 16 is a right side view thereof.

The broken lines shown in the figures are included for the purpose of illustration and form no part of the claimed design.
